UNITED STATES PATENT OFFICE

SIEVERT THEODORE ANDERSON, OF CHICAGO, ILLINOIS

DESIGN FOR A RECOIL PAD OR SIMILAR ARTICLE

Application filed May 21, 1930. Serial No. 35,711. Term of patent 14 years.

To all whom it may concern:

Be it known that I, SIEVERT THEODORE ANDERSON, a citizen of the United States, and a resident of the city of Chicago, in the county of Cook and State of Illinois, have invented a new, original, and ornamental Design for a Recoil Pad or Similar Article, of which the following is the specification, reference being had to the accompanying drawings, forming a part thereof.

In the drawings:

Fig. 1 is a front elevational view of a recoil pad showing my new design.

Fig. 2 is a side elevational view thereof.

I claim:

The ornamental design for a recoil pad or similar article, as shown.

S. THEODORE ANDERSON.
